BROWN, OF PITTSBURGH, PENNSYLVANIA.

METHOD AND APPARATUS FOR GRADING SAND.

1,191,568.

Specification of Letters Patent. Patented July 18, 1916.

Application filed July 31, 1915. Serial No. 42,936.

To all whom it may concern:

Be it known that I, FRANCIS W. H. CLAY, a citizen of the United States, residing at Edgewood Park, in the State of Pennsylvania, have invented a certain new and useful Method and Apparatus for Grading Sand, of which the following is a specification.

My invention relates generally to the art of separating masses of particles of variant size into different grades; and more particularly it relates to the grinding art wherein it is necessary to carefully and uniformly grade and separate grades of the abrasive and arrange the grades in position for easy and effective application to the grinding machine.

Heretofore the artificial grading of sand for grinding, for example, has been accomplished by dropping the sand in water and allowing it to settle in a vertical direction, which effects a stratum selection brought about by reason of the different rates of travel of particles of different surface-to-weight ratio. In certain refinements of this process, the body of water has been in the meantime moved upward against the direction of gravity in order to delay the time of settling, and thus partially suspend the particle so as to grade more slowly. Again, there have been used devices which employed the principle of varying the rate of flow of the upwardly moving or suspending body of water at various heights, in order to vary the resistance to falling, or the suspending force, in accordance with the mass and surface of the particle. In all such processes the sand is graded in vertically superposed layers, which is an inconvenient arrangement, and moreover the sand is graded not according to the actual mass of the particle, but according to the ratio between its superficial surface and weight. Also, this use of gravity alone for separating results in a small separation of grades and the amount of separation has not been under control.

In my process an accurate grading on the basis of actual mass, and a greater separation, in more convenient position, is accomplished by the use of two forces acting simultaneously,—namely, the force of gravity, and centrifugal force, or inertia. That is, I subject each particle to the constant action of two forces operating in different

directions, and thereby have a double separating effect. Briefly, I employ centrifugal force combined with the force of gravity, in order to obtain an additional and larger and better separation, than in the prior practice. These and other objects, as will hereinafter appear, may be attained by practice of the process with the apparatus as arranged for illustration in the accompanying drawing, which is a central vertical section of the apparatus, without showing the return pump or the grinding table.

On the permanent support such as the bracket 1, I provide a suspension bearing 2 which holds the cone 4 fixed on a shaft 3, to which is attached any convenient means for revolving, as the pulley 5 operated by cord 6. The shaft 3, by plate 7 and nut 8, supports the bottom 9 of the grading and storage vessel which may be composed of a cylindrical portion 10 and generally conical portion 11, which ends at the top in an outward flaring and receiving hopper 12 approaching fairly close to the cylinder 13 on the shaft 3. The sand may be fed in any convenient way as by pipe 14 and may pass through a sieve 12^a in entering the vessel. At the bottom of the cylindrical portion 10 I provide a series of concentric ring walls 15, 16, 17, dividing the vessel into storage compartments (18), (19), (20), (21). Near the top of the conical portion 11 I provide on the outside a circular overflow trough 22 having a continuation in the form of a circumferential shelf 22^a inside the vessel 11 and a series of holes 22^b to allow escape of water and mud by overflow over the trough 22 into a surrounding circular trough 23 from which it may be withdrawn in any convenient manner as by the valved pipe 24.

The storage compartments may be of any convenient size, according to the use of the apparatus, and the graded material may be removed in any convenient manner. As here shown for simplicity sake, I provide in the bottom of each compartment a series of elongated circumferential small slots 26 which may be normally covered by a flap valve in the form of a rubber ring 25, and this ring may be lifted to allow escape of sand and water by the upward movement of a finger or plunger 27 and the sand drawn off through a chute 28. For convenience in emptying the vessel upon occasion, the central shaft 3 may be hollow and have open-

ings (29) through which the water may be emptied by the valve 30 at the bottom.

In operation the vessel is completely filled with fluid of some sort, and it will be understood that as the vessel revolves the entire mass of this fluid is in circular motion. The suspending medium may be air in dealing with some substances; but in dealing with sand it is preferably water, as here shown (though sand may be graded dry in air). The sand in dropping through the water is separated laterally by centrifugal force according to the mass of each individual particle, so that the classified particles will drop into the horizontally separated storage compartments (18), (19), (20), (21), as shown, and may be drawn off as needed through the valves 25. Meantime mud and other matter not heavy enough to sink past the apron 22^a before the centrifugal force carries them out thereto, will be caught and drawn off through the troughs 22 and 23 or in any other convenient way.

Of course the theory of operation is not essential to my invention, but it is to be noted that the use of centrifugal force permits of complete control of the classification. It is a familiar law of physics that a mass acted on simultaneously by two forces at an angle to each other, and free to move, will be moved in direction and amount proportional to the diagonal of a parallelogram determined by the two forces. It will also be recalled that the surface of a particle varies with the square of the diameter; that the cubic content varies with the cube of the diameter; that the centrifugal force tending to move it varies with the square of the velocity as well as with the actual mass of the particle.

A particle at the point *o* on the dotted line diagram in the figure, and in its suspended condition in the vessel 11, will be subjected to the vertical force of gravity *o g*, and simultaneously to the horizontal centrifugal force *o f*. It would therefore in a certain time reach the point *r* by traveling approximately the line *o r*. The time of sinking through the water will determine the distance *o g* (since gravity is constant), but it will be noted also that the effective time of subjection to the centrifugal force is determined by this same time of falling; the longer the particle is suspended the greater the centrifugal force, increasing with the square of the lateral displacement. Each particle will be moved along the horizontal component with accelerated motion, and by an amount primarily governed by the actual mass of the particle. The resistance to motion through the water increases with increasing density, in both the vertical and horizontal direction, so that the lateral resistance also aids the separation into grades.

Under the conditions mentioned, by se-

lecting the proper value of the speed, and therefore the centrifugal force, and supposing the grains of sand to be of uniform material (as crushed quartz), the lighter grains will travel farthest from the center and fall in the outer compartments, and the sand will be classified in a horizontal direction according to mass. The entire vessel will be designed to fit the particular conditions of the material being classified, and the use of the classified material.

By the apparatus shown for illustration, it will be seen that the sand may be continuously introduced and continuously graded and continuously drawn off, in any order desired, and each operation is subject to control without interfering with the other operations. For example, the amount of sand stored in the horizontally arranged storage compartments, has no effect whatever upon the grading operation; the lines of classification are changed by merely changing the speed of rotation of the vessel; the degree of accuracy of grading may be modified by varying the distance of travel of the grain, and likewise the speed of grading may be governed by the designed speed of the vessel.

I believe I am the first to apply the use of centrifugal force to the grading of solid materials falling in a fluid. To the mechanic will occur many uses of the method and modifications of the suggested apparatus to fit conditions.

Having thus described my invention and illustrated its use, what I claim is the following:

1. The method of grading sand which comprises maintaining a body of water in circular motion about a vertical axis, dropping the sand through said body of water from above and separating the grades of sand horizontally in zones about the axis at equal elevation by the combined action of centrifugal force and gravity, substantially as described.

2. The method of grading sand by dropping the sand in a body of water, meantime maintaining the body of water in circular motion, and thereby subjecting each particle of sand to centrifugal force and the force of gravity, separating it into grades arranged in horizontally placed zones at equal elevation, and drawing off the sand from said zones by gravity.

3. A sand grader comprising a vessel supported on a vertically rotating axle, and having a series of horizontally arranged grading compartments in its bottom, with means for drawing off grades separately, and means for continually removing surplus water and detritus, substantially as described.

4. Sand grading apparatus comprising a vessel of water, means to constantly re-

tate it about a vertical axis, means for introducing the sand into the water at the center of the top surface, and said vessel being provided with partitions dividing the bottom portion into horizontal zones, substantially as described.

5. Sand grading apparatus comprising a circular vessel having concentric partitioning walls dividing its bottom into horizon-

tal zones, means for suspending the vessel 10 and for continually rotating it, means to introduce the sand at the center of the vessel, and means to continually draw off surplus water from the vessel, substantially as described.

15 In testimony whereof I have hereunto signed my name.

FRANCIS W. H. CLAY.
